UNITED STATES PATENT OFFICE.

CLAUDE C. LAVAL, OF PITTSBURG, PENNSYLVANIA.

SILVERING-MACHINE.

No. 813,980.

Specification of Letters Patent.

Patented Feb. 27, 1906.

Application filed May 20, 1905. Serial No. 261,480.

To all whom it may concern:

Be it known that I, CLAUDE C. LAVAL, a citizen of the United States, residing at Pittsburgh, in the county of Allegheny and State 5 of Pennsylvania, have invented new and useful Improvements in Silvering-Machines, of which the following is a specification.

This invention relates to a machine for silvering surfaces of non-metal materials, such 10 as glass, to form mirrors, reflectors, and the like.

One of the objects of the invention is the provision of mechanism for conveying the material being treated in an even and uniform manner over the bed of the machine. 15

A further object of the invention is the provision of means for evenly feeding the liquid substance to the material.

Another object of the invention is the provision of means for adjusting automatically 20 the conveying mechanism.

A still further object of the invention is the provision of means for heating the coating substance previous to its delivery to the surface treated. 25

Another object of the invention is to provide various novel adjustments of the several parts constituting said invention.

With these and other objects in view my 30 invention consists in the construction, combination, and arrangement of parts, as hereinafter described, and is embodied in the preferred form in the accompanying drawings, though I desire it to be understood that I 35 may make such changes, variations, and modifications as come properly within the scope of the claims hereunto appended without departing from the spirit of my invention.

In the drawings, Figure 1 is a view in side 40 elevation, partly in section, of the machine. Fig. 2 is a top plan view of the same. Fig. 3 is an end elevation, partly in section. Fig. 4 is a sectional view of the hopper heating and feeding means. Fig. 5 is a side elevation of 45 the bed, partially in section. Fig. 6 is a transverse vertical section of the bed and feeding means. Fig. 7 is a detail section of a portion 50 of the conveying mechanism. Fig. 8 is a detail section of the lower extremity of the hopper and the valve controlling the same.

Like characters refer to like parts throughout the several figures.

The machine consists of a supporting-table 2, having a bed 3, which has its surface provided with a cover 4, preferably of felt, fixed to the bed in any suitable manner, the cover 55

being provided to prevent the material fed over said bed from becoming scratched or injured. At opposite ends of the supporting-table 2 are brackets 5, 6, 7, and 8, the same 60 being secured to said supporting-table in a fixed manner and having journaled therein rotatable shafts 9 and 10. On the shaft 9 are adjustably fixed grooved pulleys 11 and 12, and on shaft 10 are pulleys 13 and 14. 65 The pulleys 11 and 13 are in alinement with one another and are so arranged on the shaft as to be near the side edge of the bed of the machine. Also pulleys 12 and 14 are in alinement and are so arranged on the shafts 70 9 and 10 as to be near the opposite side edge of the bed 3, and over said pulleys 11 and 13 and 12 and 14, respectively, pass endless belts 15 and 16, which are of any desired thickness. 75

Intermediate the end edges of the supporting-table 2 and the shafts 9 and 10 are positioned frictional rollers 17, 18, and 19, the same being suitably journaled in the brackets 5, 6, 7, and 8 and adapted to maintain the endless belts 15 and 16 taut. Furthermore, below the supporting-table 2 I have provided adjusting devices 20, which include rollers 21 on opposite sides of the machine engaging the endless belts 15 and 16, 85 said rollers 21 being carried on a shaft 22, and the latter mounted in slots 23 in supports 24, depending from the lower portion of the supporting-table 2. The said rollers are capable of vertical adjustment in the slots 23, so as to 90 make taut or slacken the endless belts 15 and 16. On the bed 3 of the supporting-table 2 are belt-guide members 25, 26, 27, and 28, each having pockets 29 in series. In each of the pockets 29 are shiftable L-shaped arms 95 30, which are yieldably supported in said pockets, being controlled by tension-springs 31. Rotatably connected to the inner end of the arms 30 are frictional rollers 32, the latter engaging the outer edges of the belts 100 15 and 16 and the inner portions of the belt-guide members 25, 26, 27, and 28 overhanging the belts to maintain the latter in close proximity to the bed 3 of the machine.

The frictional rollers 32 cause the endless 105 belts 15 and 16 to travel over the bed 3 of the machine in an even manner and prevent the same from becoming disarranged laterally on the bed, thus insuring proper alinement of the said belts, and as the material to be 110 treated is fed onto the bed 3 of the machine the edges thereof are engaged by the inner-

most edges of the belts 15 and 16 to convey said material throughout the entire length of the bed of the machine. The frictional rollers 32 are automatically adjustable to maintain the endless belts constantly in engagement with the material fed over the bed of the machine.

It will be apparent that the belt-guide members are capable of adjustment transversely of the machine through the medium of set-screws 33 engaging elongated slots 34 in the supporting-table.

Intermediate the ends of the supporting-table 2 and in the bed 3 of the same is a transverse feed-slot 35 to form an opening for the liquid-feeding means, which includes a feeding-trough 36, cylindrical in form and having grooved ledges 37 and 38 projecting beyond the opening 35 and below the latter. The feeding-trough is provided with a slot 39, arranged longitudinally thereof and wedge-shaped in cross-section, through which the liquid substance is fed to the material being treated through the slot 35. Said ledges 37 and 38 are for the purpose of catching the surplus liquid substance fed through the slot 39 to the material treated and is drained therefrom in any suitable manner, said feeding-trough 36 being adjustably connected to the supporting-table 2, so that the same may be raised or lowered in a vertical direction to and from the material treated. At one side of the supporting-table 2 is connected a hopper 40, having a heating-chamber 41 and a cover 42, the latter being provided with an opening 43 and a hinged cap 45, through which liquid substance is introduced into the hopper 40, the said hopper having a reduced outlet extremity and terminating in a mouth portion 44. Leading from said mouth portion 44 of the hopper 40 is a feed-pipe 46, which is connected to the feeding-trough 36. Leading to the heating-chamber 41 of the hopper 40 is a heating-pipe 46', terminating in a burner 47, whereby heat is produced in the chamber 41 of the hopper 40, so as to liquefy the substance contained in the hopper 40 previous to its being fed to the trough 36 and to maintain the same in a liquid state throughout the operation of the machine. To control the supply of substance to the feed-trough 36 through the feed-pipe 46, a valve 48 is provided, the latter having connected thereto a stem 49, terminating exteriorly of the hopper 40 and adjustably operated by a hand-wheel 50, the same engaging a threaded end 51 of said stem 49, said hand-wheel 50 being supported exteriorly of the hopper by a yoke-piece 52, which is secured to the hopper in any suitable manner. Above the bed 3 of the supporting-table 2 is a pressure-roller 53, which is yieldably supported in brackets 54 and 55. The pressure-roller 53 is for the purpose of holding the material being treated in contact with the bed 3 of the

machine and to prevent any displacement thereof when fed onto the machine.

On one end of the shaft 10 is secured a driving-pulley 56, through the medium of which motion is imparted to the endless belts 15 and 16 by any well-known source of power. An ontake-table 57 is secured to the brackets 7 and 8, so as to afford easy handling of the materials to be treated, said ontake-table 57 being so arranged as to have its upper face 75 level with the bed 3 of the machine.

In the operation of the machine motion is imparted from the driving-pulley 55 to the pulleys 13 and 14, the latter causing the endless belts 15 and 16 to travel across the bed 3 of the supporting-table 2 in a longitudinal direction, and the material is fed between the said endless belts 15 and 16 from the ontake-table 57 to the bed 3 of the supporting-table 2 and between the pressure-rollers 53 and onwardly over the feed-slot 35 and liquid-containing trough 36, where the same receives on its under face a coating of amalgam from the elongated slot 39 in said trough, and as the said material advances to the delivery 90 end of the supporting-table 2 said coating is cooled by coming in contact with the atmosphere, and when said material is delivered from the machine the same is ready for use. It is apparent that the belt-guide members 95 25, 26, 27, and 28, including the automatically-adjustable frictional rollers 32, which are yieldably supported in the pockets 29 of said guide members, cause the innermost edges of the belts to constantly contact with the edges of the material treated, thereby assuring a continuous uniform travel of said material, so that the same may be conveyed throughout the length of the bed 3 of the supporting-table. Furthermore, by having the 105 frictional rollers 32 yieldably supported in the pockets 29 of the guide members 25, 26, 27, and 28 an automatic adjustment thereof is permitted for different widths of material desired to be treated. During the feeding of the liquid substance to the material treated it may be desired to apply a coating of varying thicknesses, and to accommodate this variation the trough 36 is adjusted vertically 110 away from the supporting-table 2. The hopper 40 is arranged above said supporting-table, and the liquid substance contained therein will therefore freely flow through the elongated slot 39 and the opening 35 in the table, and should it happen that any excess 120 of liquid substance flows from said elongated slot 39 the same will be caught by the grooved ledges 37 and 38.

To control the supply of liquid substance from the hopper 40 to the feed-pipe 46, the hand-wheel 50 is manipulated, which in turn will cause the raising or lowering of the stem 49, having the valve 48, controlling the opening or mouth portion 44 of said hopper 40, so that when said stem 49 is elevated or lowered 130

the valve 48 will regulate the mouth 44 of the hopper by the opening or closing thereof and allow the contents of the hopper 40 to be admitted to or cut off from the feed-pipe 46.

5 It is evident that by having the heating-pipes 46 terminating in a burner 47 and situated in a heating chamber or compartment 41 in the hopper 40 the contents of the latter will be thoroughly heated previous to delivery to the feeding-trough 36.

10 The valve 48 at the lower end of the stem 49 is of inverted-cup shape and the body thereof provided with a plurality of elongated openings 58, and the same when brought to a closed position fit snugly into the mouth 44 of the hopper 40, and thereby insures a tight closing of said mouth 44, and when the valve is lifted from the mouth 44 to open the same the substance contained in the hopper 40 15 will flow freely through the openings 58 to the feed-pipe 46 and then into the trough 36 and subsequently to the surface of the material being treated. However, the valve may be of any other suitable construction.

25 Having thus fully described my invention, what I claim as new, and desire to secure by Letters Patent, is—

1. A machine of the class described including a supporting-table, oppositely-disposed frictional conveying means for moving material being treated over said table, means on the table for automatically adjusting said conveying means, and means for applying liquid coating substance to said material.

35 2. A machine of the class described including a supporting-table, frictional conveying mechanism thereon, means for automatically adjusting said frictional mechanism to maintain the same in contact with the material, 40 and means for feeding liquid substance to the latter.

3. A machine of the class described including a supporting-table, endless conveying mechanism at opposite sides of said table for frictionally engaging the material, automatically-adjustable guide members for the conveyers, and means for feeding a liquid coating to the material.

4. A machine of the class described including a supporting-table, an ontake-table at one end thereof, endless conveying mechanism for frictionally engaging the material, automatic guide members for said conveying mechanism, a hopper, and means co-operative therewith for feeding liquid coating to the material treated.

5. A machine of the class described including a supporting-table, rotatable endless conveying mechanism, means for adjusting the same, automatic guide members for the conveying mechanism, and means for feeding liquid coating to the material treated.

6. In a machine of the class described, a supporting-table, an ontake-table, endless belts for frictionally engaging the material to

convey the same over said table, means for adjusting the belts, automatic guide means for the latter, and means for supplying a liquid coating to said material.

7. In a machine of the class described, a supporting-table, traveling endless belts to frictionally engage the material for conveying the same over said table, adjustable guide members for said belts, automatic means for maintaining the belts in frictional engagement with the material being treated co-operative with said members, a supply-pipe, a feed-trough connected to said pipe for introducing a liquid coating to the material treated, and a hopper for supplying liquid to said feed-pipe.

8. A machine of the class described including endless conveying mechanism, adjustable guide members for the latter, and automatic, adjustable means carried by said members for maintaining the said conveying mechanism in frictional engagement with the material being treated.

9. A machine of the class described including endless conveying mechanism, adjustable guides therefor, automatic means co-operative with said guides for maintaining the said conveying mechanism in frictional engagement with the material being treated, and means for feeding a liquid coating to the material treated.

10. In a machine of the class described, a supporting-table having a conveying mechanism at opposite sides thereof, means for automatically adjusting said conveying mechanism, means for feeding a liquid coating to the material, and means for heating the said feeding means.

11. A machine of the class described including a supporting-table, pulleys at opposite sides of said table, conveyers on said pulleys, guide members for said conveyers, automatic means co-operative with said members for maintaining said conveyer in frictional engagement with the material being treated, and means for feeding liquid to the material treated.

12. A machine of the class described including a supporting-table having a transverse opening, an adjustable feed-trough below said opening, a liquid-receiving hopper having a feed-pipe communicating with said trough, a valve mechanism controlling the supply to said trough, pulleys on said table, endless conveying mechanism on said pulleys, and adjustable guides having automatic means for maintaining said conveying mechanism in frictional engagement with the material being treated.

13. A machine of the class described including a supporting-table having a transverse opening, an adjustable feed-trough below said opening, a liquid-receiving hopper having a feed-pipe communicating with said trough, a valve mechanism controlling the

supply to said trough, pulleys for said table, endless conveying mechanism on said pulleys, adjustable guides having automatic means for maintaining said mechanism in frictional engagement with the material being treated, and means for keeping said conveyer mechanism taut.

14. A machine of the class described having a supporting-table with intermediate means for feeding a coating substance thereto, and automatically-adjustable frictional edge-engaging devices for conveying the material to be coated over the table.

15. A machine of the class described having a supporting-table with an intermediate opening for feeding a coating substance therethrough, and means for frictionally engaging the material for conveying the same to be coated over the table close to said opening.

16. A machine of the class described having a supporting-table with an intermediate opening for feeding a coating substance therethrough, a receptacle adjacent to said opening for the coating substance, frictional engaging mechanism for conveying the material to be coated over the table and means for holding the material close to said opening.

17. A machine of the class described having a supporting-table with an intermediate opening for feeding a coating substance therethrough, an adjustable receptacle adjacent to said opening for the coating substance, and mechanism frictionally contacting with the material for conveying the same to be coated over the table close to said opening.

18. A machine of the class described having a supporting-table with an intermediate opening for feeding a coating substance therethrough, an adjustable receptacle under the table adjacent to the opening for the coating substance, mechanism for conveying the material to be coated over the table close to said opening, and means for automatically adjusting said mechanism to frictionally engage the same with the material.

19. A machine of the class described having a supporting-table with intermediate means for feeding a coating substance thereto, automatically-adjustable conveying mechanism, and means for regulating the feed of the coating substance to the table.

20. A machine of the class described having a supporting-table with an intermediate

opening for feeding a coating substance therethrough, an adjustable feed-receptacle having oppositely-disposed ledges, below said opening the latter extending beyond the opening, and mechanism for conveying the material to be coated over the table close to said opening.

21. A machine of the class described having a supporting-table provided with an intermediate opening, an adjustable feed-receptacle having a slot coextensive with said opening under the table adjacent to said opening, an automatically-adjustable conveying mechanism for engaging the edges of the material to be coated, and means for supplying the liquid substance to the said feed-receptacle.

22. A machine of the class described including a supporting-table having frictional edge-engaging conveying mechanism for the material, automatically-adjustable guide means for the said mechanism, and means for feeding liquid coating substance to the material.

23. A machine of the class described having a supporting-table provided with an intermediate opening, a feed-receptacle coextensive with said opening, ledges forming troughs on said receptacle below the opening and extending beyond the same, oppositely-disposed edge-engaging conveying mechanism for the material, means for automatically adjusting said mechanism, and means for supplying liquid substance to the said receptacle.

24. A machine of the class described having a liquid coating feed device for the material, automatic frictional edge-engaging mechanism for conveying the material to be coated over the table, and a yieldable pressure means above the latter.

25. A machine of the class described having automatic frictional edge-engaging mechanism for conveying the material to be coated over the same, yieldable pressure means above the table at one end thereof, and means for supplying liquid coating substance to the material.

In testimony whereof I have hereunto set my hand in presence of two subscribing witnesses.

CLAUDE C. LAVAL.
